UNITED STATES PATENT OFFICE.

NELSON WERTS, OF ST. MARYS, OHIO.

ENVELOP-FASTENER.

1,050,582.

Specification of Letters Patent. Patented Jan. 14, 1913.

Application filed May 18, 1911. Serial No. 628,056.

To all whom it may concern:

Be it known that I, NELSON WERTS, a citizen of the United States, residing at St. Marys, in the county of Auglaize, State of Ohio, have invented certain new and useful Improvements in Envelop-Fasteners; and I do hereby declare the following to be a full, clear, and exact description of the invention, such as will enable others skilled in the art to which it appertains to make and use the same.

This invention relates to envelop fasteners and the object of the invention is to provide a novel and simple device of this character which will prevent the opening of the envelop without destroying the seal thereof.

A still further object of the invention is to provide a fastener in which the parts can be constructed of sheet metal or wire and which comprises a fastening tongue attached to the flap of the envelop in a novel manner and adapted to engage a keeper secured to the body of the envelop in a novel manner.

25 A still further object is to provide a device of this character which may also be applied to boxes and the like and which will serve to insure safety in the delivery thereof.

With these and other objects in view, the invention consists of certain other combinations and arrangements of parts, as will be hereinafter more fully described and claimed, it being a still further object to provide a device which will not be likely to 35 get out of working order.

In the drawings:—Figure 1 is a plan view of an envelop with my improved fastener in its preferred embodiment applied thereto and with the flap extended. Fig. 2 is an 40 enlarged plan view of the fastener removed from the envelop and in an engaged position. Fig. 3 is a vertical sectional view taken on the line 3—3 of Fig. 2. Fig. 4 is a detailed view of the keeper plate to more 45 especially show its attaching means. Fig. 5 is a detailed perspective view of a modified form of fastener, with a sheet metal securing tongue. Fig. 6 is a detail view of a securing tongue formed of wire.

50 Referring to the drawings in detail and in Figs. 1 to 4, there is shown an envelop 10 having the usual closing flap 11 provided with an adhesive covering 12 by which the envelop is sealed.

55 In order to prevent opening of the envelop without destroying the seal, I pro-

vide a plate 13 of sheet metal and which is comparatively long and narrow and which is provided with beveled corners 14 to prevent the same from causing injury by reason of sharp corners excepting when attempting to open the envelop. Said plate is extended lengthwise of the envelop. In order to secure the plate to the outside of the flap 11, it is provided with tongues 15 formed by striking out portions of the metal as shown at 16 and bending the same inwardly to extend through transverse openings 17 in a securing plate 18. This plate 18 also has its corners beveled as shown at 14 and the openings 17 are in line with the tongues which when extended therethrough after piercing the flap are turned outwardly as shown at 19 in contact with the plate 18.

A keeper plate 20 formed in a similar 75 manner as the plate 13 is secured to the back of the envelop body upon its outer surface by a plate 21 which is also formed in a similar manner as the plate 18 and serves to secure the keeper plate 20 in position for engagement by a securing tongue 22 which is disposed beneath the plate 18 and has a rebent end 23 frictionally contacting with the outer face of said plate to dispose the tongue over the adhesive covering of the flap. The 85 free end of the tongue is rebent in an opposite direction from the portion 23 as shown at 24 so that when the flap is closed down and sealed, said portion 24 will engage the lower edge of the plate 20 and between the 90 latter plate and the back of the envelop and plate 21 thereby efficiently serving to prevent opening of the envelop without breaking the seal.

In Fig. 5 of the drawings I have shown 95 the fastener formed of wire with the exception of the tongue and in this instance, a short section of wire 25 has its ends extended through the flap of the envelop or of a box if desired so as to provide inwardly projecting portions 26 adapted to be engaged by eyes 27 formed at the ends of a securing member 28 inwardly of the flap and which is also formed of wire. A short section of wire 29 is secured upon the inner side of the 105 back of the envelop or box over which the flap extends to form projecting portions 30 similar to the portions 26 and a keeper 31 formed in a similar manner as the portion 28 is secured thereto for engagement by the 110 tapered hook extremity 32 or rebent portion at the free end of the tongue 33. This

- tongue is also rebent as shown at 34 to engage the securing member 28 and when the flap is folded, the rebent portion 32 engages beneath the keeper 31 to secure the same in position or if desired a single section of wire 35 having rebent ends 36 and 37 may be employed instead of the tongue 33, thereby permitting this fastener to be constructed wholly of wire.
- 10 From the foregoing description, it will be apparent that I have provided a novel form of fastener which will efficiently serve the purpose intended and in carrying out the use of the invention it is desirable that when 15 an envelop or a box is to be delivered, it be numbered and recorded by the postal authorities, thereby further insuring safe delivery. The fastener may be formed of a few simple parts, either of wire or sheet 20 metal and will thus prove economical in the manufacture.

I claim:—

1. An envelop fastener comprising a member having intermediate portions extending 25 through the flap of the envelop from the outside, a securing member engaged by said portions at the inside of said flap, a keeper similarly attached to the body of the envelop and a tongue having its ends rebent toward a 30 common side and engaged between the se-

curing member and flap and beneath the keeper respectively, whereby the flap will cover the same when closed.

2. A fastener for receptacles having a flap and body portion, comprising a section of metal having portions thereof projecting through the flap toward its inner side and extending outwardly, a securing member of less length than said section and having openings engaged by said projecting portions for contact with the inner face thereof to retain the same in position, similar sections secured to the body, the projecting portions extending inwardly of the body for holding the securing member and a metallic tongue having rebent ends located in a common plane, one end being extended beneath the securing member of the flap and frictionally engaging one edge thereof to extend over its sealing portion for frictional engagement of the other end beneath the keeper carried by the body when the flap is sealed.

In testimony whereof, I affix my signature, in presence of two witnesses.

NELSON WERTS.
